UNITED STATES PATENT OFFICE.

MIROSLAV STÖHR, OF PRAGUE, CZECHOSLOVAKIA.

FIRE GRATE.

Application filed June 11, 1926, Serial No. 115,363, and in Germany March 19, 1925.

This invention relates to a fire grate provided with slidable means for removing the clinkers, said grate being capable of movement longitudinally and laterally of the 5 furnace by means of a bar projecting out of the furnace, the latter also acting to operate the slidable clinker removing means. The invention also includes the provision of supporting surfaces on the grate which rest on stationary bearers and are made arcuate, so that the grate when it is shaken, moves to and fro horizontally and vertically. The invention also relates to the arrangement of the clinker removing grate, the sections of 10 which are housed in the frame of the grate at the under surface thereof and move with the grate during the horizontal and vertical shaking motions and in addition are capable of being adjusted to provide a full or partial opening for the clinkers to fall through.

In the accompanying drawing a constructional form of a grate is shown, Fig. 1 being a plan view, Fig. 2 a section on line 2-2 of Fig. 1, Fig. 3 is a section on line 25 3-3 of Fig. 1 with the clinker removing grate in a closed position and Figs. 4 and 5 are similar sectional views showing the clinker removing grate in partially open and fully open positions respectively.

30 The frame grate R has its sides bevelled downwards towards the inside. According to the invention the lower surfaces S of the sides of the frame, which rest on the bearers P are arcuate. Under the edge of the opening in the frame of the grate a guide K is provided connected to the frame, in which guide a clinker-removing grate V₁, V₂ consisting of two or more parts is slidable. The parts of this clinker-removing grate, when 35 in the position in which they fill the opening in the frame, lie offset or stepped with respect to each other. The position of the upper part V₂ of the clinker-removing grate is limited inwardly by a stop member Z. The 40 lower part V₁ of the clinker-removing grate is connected to the shaking or pushing bar T and its motion is transmitted to the upper part V₂ by projections 1, 2 provided on the edges of the parts V₁ and V₂ engaging one 45 another mutually.

50 The push bar T may be coupled to the frame R of the grate. For this purpose on a shield r connected to the frame of the grate staples r' are provided, in which a sliding member s is capable of sliding trans-

versely to the direction in which the bar T is pushed. On the lower side of the sliding member s is a recess s' (Figs. 4 and 5). When the sliding member s is so placed that its recess s' lies above the bar T which passes 60 through an opening in the shield r of the frame of the grate, the bar T can be raised so as to move a tooth o on the said bar from the front side of the shield r to the rear side of the same (Fig. 3). On the sliding member s being slid so that its lower edge rests against the bar T, the bar will be coupled to the body of the grate, so that the latter must take part in the movements of the bar T. This coupling of the parts is effected on 65 the one hand by the tooth o on the bar T and the connection of the latter to the part V₁, which is secured relatively to the part V₂, by the latter part resting against the stop Z, ensuring the simultaneous movement of the 70 bar and the grates in the horizontal plane, and on the other hand by the bar T in the recess of the shield r being coupled by the sliding member s to the body of the grate in the vertical direction.

80 The arrangement operates in the following manner:

The bar T being connected in the manner already described to the body of the grate, the latter can be moved forwards and backwards and also laterally. The body of the grate will however also be moved upwards and downwards, through the arcuate supporting surfaces S sliding on the bearers of 85 the grate.

In order to partially or wholly remove the coarse clinker, the bar T is uncoupled from the body of the grate R. For this purpose the sliding member s must be again slid in such a manner that its recess s' will lie above 90 the bar T. The latter can then be lifted with its tooth o over the lower edge of the slot in the shield r. The displacement of the bar T will then have no effect on the body of the grate and will only act on the clinker 95 removing grate in the following manner. On the bar T being moved in the direction of the arrow x (Fig. 3) the bar V₁ will first be moved alone. When it has been slid along till it is below the part V₂, the latter will take 100 part in the motion, due to the coaction of the stop members 1, 2, and finally the whole of the opening in the frame of the grate will 105 be left unobstructed (Fig. 5).

110 On the bar T being moved in the opposite

direction, the bar V_1 will first be slid by itself into the inner part of the grate body. The part V_1 will then carry the part V_2 along with it, through the stop bars 1, 2 engaging with one another, until the part V_2 rests against the stop member Z. In this position the parts V_1 and V_2 will completely fill the opening in the body of the grate. On the part V_1 reaching this extreme position the tooth o on the bar T will come against the inside of the shield r so that the bar T can again be coupled to the body of the grate in the manner already described.

What I claim is:

- 15 1. A shaking grate for furnaces, comprising in combination a grate body, stationary bearers for supporting the grate body, means for moving the grate body longitudinally and laterally on the said bearers, a clinker-removing grate capable of sliding in the said grate body and arcuate surfaces on the under side of the grate body, where it rests on the said bearers, for the purpose, when the grate body is moved longitudinally and laterally
- 20

for also imparting to it a vertical motion as 25 and for the purpose set forth.

2. A shaking grate for furnaces comprising in combination a grate body, stationary bearers for supporting the grate body, a bar for removing the grate body longitudinally 30 and laterally on the said bearers, clinker-removing grates, a plurality of superposed guides on the under side of the grate body in which the clinker-removing grates can slide one over the other longitudinally, the 35 said bar being operably connected with the clinker-removing grates, means for releasably fixing the bar to the grate body and arcuate surfaces on the under side of the grate body, where it rests on the said bearers, for the 40 purpose, when the grate body is moved longitudinally and laterally for also imparting to it a vertical motion, as and for the purpose set forth.

In testimony whereof I have signed my 45 name to this specification.

MIROSLAV STÖHR.
